ATTORNEY

UNITED STATES PATENT OFFICE

2,324,578

BOTTLING MACHINE

Francis C. Hamilton, Chattanooga, Tenn., assignor of one-half to L. Ray Schuessler, St. Louis, Mo.

Original application March 4, 1939, Serial No. 259,756. Divided and this application May 7, 1942, Serial No. 442,006

7 Claims. (Cl. 226—2)

This invention relates generally to bottling machines and more specifically to bottling machines adapted for use in bottling beverages with sippers sealed within the bottles containing the beverage, the predominant object of the invention being to provide a bottling machine having means for feeding sippers into bottles in which beverages are being bottled with the aid of the machine, with means for offsetting the tendency of the sippers to float upwardly in the beverage within the bottles as said bottles approach the capping mechanism of the bottling machine.

As is quite generally known to persons familiar with such matters, bottling machines, of the type to which this invention relates, ordinarily include conveyor means by which lines of bottles are conducted through the machines, such bottles receiving amounts of syrup, water, and gas as they pass into operative relation with respect to various parts of the machines, and the bottles being capped as said bottles pass into operative relation with respect to the capping mechanism of the machines. The improved bottling machine to which this invention relates includes means for automatically dropping a sipper in each bottle as it passes the position of the sipper feeding mechanism of the machine, and also, because the subsequent introduction of liquid into the bottles tends to cause the sippers so introduced into the bottles by the sipper feeding means to float upwardly within the bottles, the improved machine includes baffle means which controls upward floating movement of the sipper of each bottle as said bottle approaches the capping mechanism of the machine, and thereby assures passage of the sipper beneath the cap to be applied to the bottle by said capping mechanism.

Fig. 1 is a fragmentary front elevation of a bottling machine constructed and arranged in accordance with this invention.

Fig. 2 is an enlarged vertical section taken on line 2—2 of Fig. 1.

Fig. 3 is an enlarged horizontal section taken on line 3—3 of Fig. 1.

Fig. 4 is a fragmentary elevation of the parts illustrated in Fig. 3.

Fig. 5 is a fragmentary, horizontal section taken on line 5—5 of Fig. 2.

In the drawing, wherein is shown for the purpose of illustration, merely, one embodiment of the invention, A designates in Fig. 1 a bottling machine of conventional construction and arrangement. The bottling machine A includes a base B which aids in supporting the mechanism of the bottling machine, said mechanism includ-

ing a conveyor C by which bottles to be filled and capped by the bottling machine are conducted through the machine. The bottling machine A includes, also, means D which serves to introduce syrup into the bottles during their passage through the machine, means E for introducing water into the bottles, means for carbonating the contents of the bottles when this is desired, and means F for capping the bottles after they have been filled. Due to the fact that the construction and mode of operation of bottling machines of the type to which this invention relates are well known to persons skilled in the art to which this invention relates, it will not be necessary to describe same beyond a point where a complete understanding of the present invention may be had. In addition to the construction and arrangement of the conventional bottling machine, the machine illustrated in Fig. 1 includes means G for feeding sippers one at a time to bottles as said bottles move successively with respect to the position of the sipper feeding means, said sipper feeding means being constructed and arranged in accordance with the sipper feeding means described and claimed in an application for United States Letters Patent Serial No. 259,756, now Patent No. 2,282,576, filed March 4, 1939, in the names of Francis C. Hamilton and Elmer C. Landhoit, of which application the present application is a division. Also the bottling machine illustrated in Fig. 1 includes means for preventing excessive upward floating movement of the sippers in the bottles as said bottles approach the capping mechanism of the bottling machine so that said sippers may move beneath said capping mechanism, the last mentioned means constituting the novel feature of the present invention.

The sipper feeding means G of the bottling machine A comprises a housing I wherein the sipper feeding mechanism (not shown) is disposed, said housing being provided at its bottom with a pair of brackets 7 having each a tubular socket 8 associated therewith. Extended into the sockets 8, and fixed therein by means of set screws 4, are pipes 5, said pipes each having fixed thereto a pair of brackets 6 which are secured by set screws 7 to upper and lower angle members Ca which constitute parts of the conveyor means of the bottling machine A (Fig. 2). Thus the housing I of the sipper feeding means is secured to and is supported by said angle members Ca of the bottling machine. Extended from the interior of the housing I of the sipper feeding means G is a shaft 8 which has fixed thereto a star wheel

9 which is shown to the best advantage in Fig. 5. Included as parts of the bottling machine A is a pair of vertically spaced guide bars H which are disposed adjacent to and above the outer edge of the conveyor C of the bottling machine, and a pair of similar vertically spaced guide bars J which are disposed adjacent to and above the inner edge of said conveyor C of the bottling machine. The function performed by the guide bars H and J is to prevent accidental displacement of bottles from the conveyor as said bottles are moved by said conveyor. In order that a part of the bottling machine A may perform its intended function to better advantage a guide member 10 is provided. This guide member is shaped in plan as shown in Fig. 5 and is attached at its opposite ends to arms 11 which are secured, as shown in Fig. 2, to the angle member Cb which forms a part of the conveyor of the bottling machine. The guide member 10 serves to force the bottles moving with conveyor C of the bottling machine toward the guide bars J so that said bottles will successively engage the star wheel 9 at the lower end of the shaft 8 as shown in Figs. 2 and 5 in a manner and for a purpose to be hereinafter set forth.

In the operation of the bottling machine A the bottles to be filled and capped by the machine are conveyed by the conveyor C of the machine past the location of the sippier feeding means G and as each bottle engages the star wheel 9 and continues its movement with the conveyor of the machine the star wheel is rotated a portion of a revolution. This rotary movement of the star wheel 9 is transmitted by the shaft 8 to the sippier feeding mechanism located within the housing 1 with the result that a sippier is discharged through a discharge opening in the bottom wall of said housing into the open mouth of the bottle which is in engagement with the star wheel 9. After the sippiers have been introduced into the bottles as described said bottles move on to the point in the operation of the machine where syrup is introduced into the bottles, then to the point where water is introduced into the bottles, and then to the point where the bottles are capped. When water is introduced into the bottles during operation of the bottling machine there is a tendency for the sippiers in said bottles to float upwardly therein, and if this tendency were not controlled the sippiers might, in some cases at least, be extended upwardly to such extent that they would not pass beneath the capping mechanism of the bottling machine.

In view of this situation the bottling machine A of the present invention is provided with a baffle 12 which is in the form of a flat plate, curved as shown in Fig. 3, in accordance with the path of travel of the bottles. The baffle is supported by brackets 13 to which it is secured at the upper ends thereof, the brackets being fixed at their lower ends to a stationary part of the machine. As shown in Figs. 3 and 4 the baffle 12 has an upwardly curved end portion 14 which is disposed at the charging head K of the bottling machine and as each bottle passes from said charging head the upper end of the sippier therein moves into engagement with said curved portion and is depressed thereby so that said upper end of the sippier may ride under the baffle during its movement from the charging head to the capping mechanism F. The baffle 12 terminates immediately adjacent to the head F of the capping mechanism and as the sippier

of each bottle passes out of contact with the baffle it moves beneath the head of the capping mechanism in such position that the cap being applied to the bottle will force the sippier down into the bottle as the capping mechanism applies the cap to the bottle.

From the foregoing it is plain that during the operation of the improved machine assembly disclosed herein a sippier is introduced into each 10 bottle and the tendency of the buoyant sippier to float upwardly in the liquid introduced into the bottle is controlled so that the presence of the sippier in the bottles does not interfere with the operations of capping the bottles. Thus as 15 each bottle leaves the machine it has a sippier sealed therein and ready for use when the cap of the bottle is removed.

I claim:

1. A bottling machine adapted to seal sippiers 20 in bottles in which fluid is bottled by the bottling machine, including means for moving bottles through the machine, and means for restraining the sippiers from moving upwardly in the fluid within the bottles prior to the sealing of said bottles, said means comprising a plate in contact with the lower face of which said sippiers move as the bottles in which said sippiers are located travel relative to said means.

2. A bottling machine adapted to seal sippiers 30 in bottles in which fluid is bottled by the bottling machine, including means for moving bottles through the machine, and means for restraining the sippiers from moving upwardly in the fluid within the bottles prior to the sealing of said bottles, said means comprising a plate 35 shaped to conform with the path of travel of the bottles moving through the machine and adapted to receive in contact with the lower face thereof the sippiers located in the bottles as said bottles move relative to said means.

3. A bottling machine adapted to seal sippiers 40 in bottles in which fluid is bottled by the bottling machine, including means for moving bottles through the machine, and means for restraining the sippiers from moving upwardly in the fluid within the bottles prior to the sealing of said bottles, said means comprising a plate shaped 45 to conform with the path of travel of the bottles moving through the machine and adapted to receive in contact with the lower face thereof the sippiers located in the bottles as said bottles move relative to said means, said plate having an end portion shaped to depress said sippiers to cause them to pass beneath the plate and move with the bottles in contact with the lower face of said plate.

4. A bottling machine adapted to seal sippiers 50 in bottles in which fluid is bottled by the bottling machine, including conveyor means for moving bottles through the machine, a charging head 60 for introducing fluid in the bottles moving through the machine, mechanism for capping the bottles, and means interposed between said charging head and said capping mechanism for restraining the sippiers from moving upwardly in the fluid within the bottles as said bottles approach the capping mechanism.

5. A bottling machine adapted to seal sippiers 65 in bottles in which fluid is bottled by the bottling machine, including conveyor means for moving bottles through the machine, a charging head 70 for introducing fluid in the bottles moving through the machine, mechanism for capping the bottles, and means interposed between said charging head and said capping mechanism for

restraining the sippers from moving upwardly in the fluid within the bottles as said bottles approach the capping mechanism, said sipper restraining means comprising a plate in contact with the lower face of which said sippers move.

6. A bottling machine adapted to seal sippers in bottles in which fluid is bottled by the bottling machine, including means for moving bottles through the machine, a charging head for introducing fluid in the bottles moving through the machine, mechanism for capping the bottles, and means interposed between said charging head and said capping mechanism for restraining the sippers from moving upwardly in the fluid within the bottles as said bottles approach the capping mechanism, said sipper restraining means comprising a plate shaped to conform with the path of travel of the bottles and in contact with the lower face of which said sippers move.

7. A bottling machine adapted to seal sippers

in bottles in which fluid is bottled by the bottling machine, including conveyor means for moving bottles through the machine, a charging head for introducing fluid in the bottles moving through the machine, mechanism for capping the bottles, and means interposed between said charging head and said capping mechanism for restraining the sippers from moving upwardly in the fluid within the bottles as said bottles approach the capping mechanism, said sipper restraining means comprising a plate shaped to conform with the path of travel of the bottles and in contact with the lower face of which said sippers move, said plate having an end portion which is located adjacent to said charging head and is shaped to depress said sippers to cause them to pass beneath said plate and move with the bottles in contact with the lower face of said plate.
